UNITED STATES PATENT OFFICE

136,424

DESIGN FOR A GAME BOARD

John S. Tremper, Bethlehem, Pa.

Application June 19, 1943, Serial No. 110,489

Term of patent 14 years

To all whom it may concern:

Be it known that I, John S. Tremper, a citizen of the United States, residing at 715 Fiot Avenue, Bethlehem, in the county of Northampton and State of Pennsylvania, have invented a new, original, and ornamental Design for a Game Board, of which the following is a specification, reference being had to the accompanying drawing, forming part thereof.

I claim:

The ornamental design for a game board, as shown.

JOHN S. TREMPER.
